UNITED STATES PATENT OFFICE

JOHN R. NEELANDS, OF LOS ANGELES, CALIFORNIA

DESIGN FOR AN APRON

Application filed July 5, 1929. Serial No. 31,948. Term of patent 3½ years.

To all whom it may concern:

Be it known that I, JOHN R. NEELANDS, a citizen of the United States, residing at Los Angeles, in the county of Los Angeles and State of California, have invented a new, original, and ornamental Design for an Apron, of which the following is a specification, reference being had to the accompanying drawing, forming a part thereof.

The figure of the drawing is a perspective view of the apron showing my new design.

I claim:

The ornamental design for an apron as shown.

JOHN R. NEELANDS.
